SPOOL AND COIL BODY

Hans D. Isenberg, Chicago, Ill.

Application April 27, 1933, Serial No. 668,154

3 Claims. (Cl. 175—21)

The invention relates to spools, and particularly to spools and coil bodies or bobbins, for electrical coils.

Such a coil body may comprise a tubular, round or prismatic central portion provided with a flange at either end. It is usually made from a plurality of suitably shaped pieces which are assembled, and finally glued and pressed together to form a unit. There are several methods known for manufacturing such coil bodies. However, expenses per coil are relatively high due to the necessity for expensive machinery and relatively complicated manual assembly labor. In some cases, depending upon the particular structure of the bodies, there is also a considerable waste of material. Another important point should be taken into account, namely, the performance of such glued coil bodies when subjected to certain operating conditions, particularly in the presence of humidity and high temperatures. The glued portions may warp or crack and affect the coil detrimentally. Difficulties occur frequently in the case of such coils placed in high tension circuits. The glue may deteriorate and cause or support electrolytic action with attendant or subsequent trouble to the performance of the apparatus. Consideration must also be given to the space available on such a spool for accommodating the windings. Since some of the space is taken up by the glued overlapping flanges or portions thereof and by the assembled and glued tubular barrel of the coil body, it is apparent that the required winding space can only be achieved by increasing the over-all dimensions of the coil body. In other words, most of these glued and pressed spools cause at least some waste of winding or assembly space. This is particularly of importance in the case of devices, such as transformer coils and the like, and in the case of apparatus using a plurality of coils in a crowded space.

My invention, which is illustrated in several embodiments in the accompanying drawings, eliminates the above noted and other drawbacks. I use, in certain embodiments, a minimum number of stamped or punched parts, formed with a view to keep down the stamping costs. These parts are simply assembled to form the desired spool. No gluing is required. The individual parts are all so designed and formed with interlocking serrations as to render support and rigidity to the assembly. A simple operation may be added to press certain parts into place so as to lend additional strength to the coil body. Certain parts, such as the flanges, may be formed so as to accommodate terminals. Any suitable material, such as hard paper, bakelite, or the like, or the customary insulating material employed for making the coil bodies intimated previously may be used for forming my novel spools.

The cost of making such a spool is practically limited to the expense for the material and the punching or stamping operation. There is no rule or limitation as to the time of making the spools. They may be made immediately prior to their use or may be made ahead of their use, and they may be stored or shipped as desired. The resulting product will be found to be superior to the spools now known and in use. The cost of the spools will be considerably less than the cost of the spools now available.

The invention is adapted to be used in connection with circular or prismatic spools. It is also possible to employ the invention for the manufacture of a composite coil body, i. e., one in which certain parts are prismatic and others are circular.

I will now describe my invention with reference to the drawing, in which

Fig. 1 shows a flange for a spool made according to one embodiment of my invention;

Figs. 2 and 3 show a blank designed to form the central tubular portion or barrel for the spool;

Fig. 4 shows a perspective view of the assembled spool; and

Figs. 5, 6, 7, and 8 illustrate corresponding elements for a spool according to another embodiment of my invention.

Referring now to the drawing, Figs. 1 to 4, inclusive, it will be seen that each of the flanges for the embodiment shown in these figures may be formed according to the structure shown in Fig. 1. The body of the flange which may be made of a suitable flat insulating material is indicated by the numeral 11. The flange is provided with a central opening having a number of serrations or locking teeth such as indicated by the numeral 12. Numerals 13 and 14 indicate holes or openings for taking terminal clips or the like. If desired the terminals may be provided directly on the flanges simultaneously with the punching operation.

The blank for forming the central portion or barrel of the coil body is particularly shown in Figs. 2 and 3. It comprises a punched or stamped strip 15 made of suitable insulating material. At one end of the strip is a locking notch 16 and at the other end of the strip is a locking tooth 17. On either side of the strip are a number of locking notches such as 18 and 19. On the face of the blank 15 are provided a number of transverse grooves such as 20, 21 and 22. It should be observed that I have provided as many notches on either side of the blank 15 as there are projections or locking teeth in the center of the corresponding flange for the barrel.

The blank is folded along the transverse grooves 20, 21 and 22 to form a tubular prismatic barrel. The locking tooth 17 will then register and engage the locking notch 16. This will prevent a

lateral distortion of the tubular barrel. The folding points will be clean and smooth due to the transverse grooves provided on the face of the blank which relieve any surface tension in the material upon folding of the same.

After the barrel is formed as above described, the flanges 11, one on either side, are attached to the barrel as is particularly shown in Fig. 4. It will be seen that the locking serrations or teeth on each side of the barrel engage the corresponding serrations in the central opening of the corresponding flanges. The result is a rigid self-supporting assembly such as is shown in Fig. 4. The depth of the notches 18-19 on the sides of the barrel blank corresponds substantially to the thickness of the flange material and, accordingly, the face of the flange on the assembled spool will be smooth and free of projections or bulges. This preserves space for assembly. A lateral displacement or distortion of the barrel is excluded due to the serrations at the ends of the blank 15 which register and engage one another. Nevertheless, there will be a natural tension in the material acting outwardly, with the result that a pressure is exerted upon the supporting walls of the openings in the flanges. This also will contribute toward providing strength and rigidity to the spool. It may be desirable in the case of certain spools to provide additional strength and rigidity and to prevent the slipping of the flanges from the barrel. This may be done by inserting into the tubular barrel a suitably shaped mandrel and punching the serrations of the barrel into and against the material of the flanges. It should be noted that the apparatus necessary for this punching operation is extremely simple and can be provided at a very low cost. The flanges are then definitely locked in any direction on the barrel and the spool is ready for use. Attention is called to the simplicity of the spool structure and to the economy in the use of material which results in a spool having maximum effective winding space and minimum effective assembly dimensions.

It will be seen upon examining the blanks 11 and 15 shown in Figs. 1 and 2 that stamping and punching tools are required for the manufacture of these blanks which might be relatively expensive due to the serrations or locking teeth on the sides and ends of the blank 15 and the serrations or locking teeth within the opening of the blank 11.

The embodiment shown in the Figs. 5 to 8, inclusive, eliminates the necessity for such relatively expensive tools employed in the manufacture of the blanks. I use in this embodiment a flange such as the one shown in Fig. 5 designated by the numeral 23. This flange is again made of a suitable flat material with an opening 24 having straight and smooth walls. Holes, such as 25 and 26 may again be provided in the blank of the flange for the purpose of receiving terminals, or, terminals may be secured to these blanks directly. It will be seen that the provision of the simple opening 24 necessitates but a simple punching tool and the manufacture of this blank will, therefore, be cheaper than the blank shown in Fig. 1.

The barrel for this embodiment of the invention is formed from a blank 27 as shown in Figs. 6 and 7. The ends of this blank are again provided with serrations or locking notches and teeth indicated by the reference numerals 28 and 29 but the sides are in the form of straight line edges.

Transverse grooves at the places where the blank

is to be folded are also provided as indicated at 30, 31 and 32. In order to determine the assembly of the flanges on the completely folded barrel, I also provide on either side of the blank 27 a number of bosses or projections indicated by the numerals 33 to 36 and 37 to 40, respectively. These projections are punched out from the material in one operation upon making the blank 27. They serve the purpose of accurately placing and supporting each flange on either side of the barrel as is indicated in Fig. 8.

The blank 27 is folded along the grooves 30 to 32, inclusive, in the same manner as was the blank 15, discussed in connection with the previously described structure. The locking tooth 29 will engage and register with the locking notch 28 and hold the barrel against lateral distortion. A flange such as the one shown in Fig. 5 is then secured one on each end of the barrel, resulting in the assembly shown in Fig. 8. It should be noted that the locking tooth 29 is approximately of the thickness of the material and that the depth of the notch 28 is accordingly dimensioned. The same is true with regard to the corresponding locking provisions on the previously discussed blank as indicated in connection with the description of the previous embodiment. The spool will again be self-supporting without any gluing. Additional rigidity and strength may be provided by preserving the smooth straight edges of the barrel on either end into and against the material of the flanges by means of a simple punching operation, substantially in the same manner as discussed with the structure shown in the previously explained figures.

I have shown and discussed above two embodiments of spools of prismatic structure. It should be understood, however, that substantially the same structure can be employed for manufacturing circular spools.

I claim:

1. A self-supporting spool for electrical coils, comprising a barrel portion consisting of a single member made of flat insulating material, locking means on each end of said member for interlocking said ends to hold said barrel against lateral distortion, locking means on the body of said barrel near the sides thereof and a flange made of flat insulating material for attachment to each side of said barrel engaging and interlocking with said second named locking means to hold said spool against longitudinal and radial distortion.

2. A self-supporting spool for electrical coils of the class described, comprising a single insulating member forming a strip, serrations at each end of said strip, said strip being shaped end to end to form the central barrel of said spool with said serrations interlocking to hold said formed barrel against distortion, locking means on each side of said barrel, said locking means projecting from the body of said barrel and being integral therewith, and a flange made of flat insulating material secured on each side of said barrel and held by said locking means.

3. A prismatic spool for electrical coils of the class described, comprising a single strip of flat insulating material, transverse grooves on said strip, said strip being folded along said grooves to form the barrel of said spool, means integral with said strip for mechanically interlocking the ends thereof in forming said barrel, a flange made of flat insulating material secured to each end of said barrel, and means integral with said barrel for locking each flange in place with the corresponding side of said barrel.

HANS D. ISENBERG.
